2 SHEETS—SHEET 2.

UNITED STATES PATENT OFFICE.

EDGAR BUELL, OF CLINTON, CONNECTICUT.

PRUNING-SHEARS.

1,137,380.

Specification of Letters Patent.

Patented Apr. 27, 1915.

Application filed December 4, 1914. Serial No. 875,427.

To all whom it may concern:

Be it known that I, EDGAR BUELL, a citizen of the United States, residing at Clinton, county of Middlesex, State of Connecticut, have invented certain new and useful improvements in Pruning-Shears, of which the following is a full, clear, and exact description.

My invention relates to shears particularly useful for pruning purposes, the object, broadly speaking, being to improve such a tool in a variety of ways and so as to render it extremely powerful, durable and effective, and yet reasonably simple in its construction.

In the accompanying drawings: Figure 1 is a side elevation of my improved pruning shears with the blades open, one of the handles being partially broken away. Fig. 2 is a similar view of the complete device with the blades closed. Fig. 3 is a view of the reverse side of the blades and adjacent parts. Fig. 4 is an edge view of the tool looking from the plane indicated at 4-4 on Fig. 2. Figs. 5, 6 and 7 are perspective views of detached details. Fig. 8 is a view of a slight modification of one of the blades. Fig. 9 is a view in general similar to Fig. 3, showing a modification.

1, 2 are the blades.

3, 4 are the handles.

The blade 1 is rigidly carried by the handle 3, while the blade 2 is connected to and operated by the handle 4. The blade 1, in its preferred form, is provided with an outwardly curved sharp cutting edge 1^a, while the blade 2 is provided with a reversely curved relatively blunt cutting edge. This edge is transversely notched, so as to form 40 preferably, backwardly faced teeth 2^a, 2^a.

5 is a forwardly faced abutment at the inner end of the handle 3, providing a forwardly faced shoulder against which the inner end of the movable blade member moves 45 and by which the strain was taken. This movable blade member comprises what I have already characterized the blade 2, and also a lateral extension or bend 6, which is by a pivot screw 6^b connected to the forward 50 end of the handle 4. The handle 4 is provided with an offset bearing lug 7 which is pivotally connected at 8 to the abutment 5, said pivotal connection being just below and relatively close to the pivotal connection 6^b, 55 whereby the movement of the handle 4 will

exert an exceedingly powerful leverage on the blades. Any suitable means, such as a screw 9, may be employed to hold the blade members 1, 2 against each other with the proper degree of firmness to cause a shearing action to take place as their cutting edges move past each other. The back of the bend 6 bears against the forward end of the abutment 5, and this back is properly curved to provide in effect a cam shoulder 6^a, which 60 coacts with the end of said abutment.

10 is a spring serving to move the handles 3, 4 apart, so as to cause the blades 1, 2 to normally move apart or open.

11 is a guard against which the forefinger 70 may rest to prevent the user's hand from sliding too far down the handles. It is preferable that the blade 1 should be made of properly tempered steel, and since it is unnecessary to form the handles of such a 75 grade of material, it is preferable that said blade 1 should be made separately from the handle by which it is carried and secured thereto as by screws or rivets 12, 12. To that end the handle 3 may have a side wing 80 14 extending forwardly from the abutment 5 against which the blade 1 may be secured and supported as shown. Another advantage from this construction is that in the event either blade becomes unduly worn, or 85 broken, it may be replaced by a new one with but little expense and without discarding the balance of the tool.

In operation, the act of pinching the handles 3, 4 together causes the blades to approach each other so as to grip and cut anything which may be placed between them. The presence of the notches or teeth at the edge of the blade member 2 prevent anything that is placed between them for cutting from being forced forwardly out of the blade engagement by the shearing action of the blades. As the handles approach each other the cam 6^a travels along the forward end of the abutment 5, so that the strain of 100 the work is received wholly by said abutment and not by the screw 9, for example. Furthermore, in the preferred form, the design of the cam shoulder 6^a is such that the action of the blade 1 on the thing being cut 105 will be a slight drawing action instead of a direct pinching action. By this slight drawing action greater efficiency is obtained. It is obvious that this drawing action may be varied by modifying the design of the cam 110

and coöperating abutment face or shoulder, an illustration of a more bulging cam being shown at 6^a in Fig. 8.

As shown in Fig. 9 the pivotal screw connection between the bend 6 and the handle 4 may be varied by providing several positions for receiving the pivot 6^b, two positions being shown at 15—15. By shifting the pivot screw 6^b the leverage may be varied. By providing the notches or teeth 2^a upon the concavely curved blade instead of on the convexly curved edge, I have found that the thing being cut is more readily severed and that there is less tendency to displacement than would be the case were the notches or teeth formed upon the convexly curved blade edge. I may also provide a stop to hold the blades closed, or practically closed, said stop in its preferred form comprising a swinging arm 16 frictionally mounted under the head of the pivot screw 6^b and being arranged to swing into position between said pivot screw and the head of the screw 9 when the blades are closed (see dotted lines Fig. 2) thus preventing the handle from opening under the action of the spring 10. While it is preferable to relieve the screw 9 from the strain of the work and to provide a separate abutment 5 to receive said strain, it is obvious that in some modifications, the screw 9 might perform partly, or wholly, the function of said abutment as well as its own function, but in all instances the slot 6^a in the bend 6 through which the screw passes should be so designed as to permit the bend 6 to move to and fro without binding.

While I have shown and described my invention in its preferred form it will of course be understood that I may make modifications and changes therein without departing from the spirit and scope of the invention as set forth in the following claims.

What I claim and desire to secure by Letters Patent is:

1. In a cutting tool of the character described, a pair of blades, a pair of handles, one blade being rigidly connected to one of said handles, a forwardly faced shouldered abutment on the same handle, an offset bend at the rear of the other blade bearing upon and supported against strain by said abutment, said offset bend being pivotally connected to the other handle, the latter being pivotally connected to the first mentioned handle to the rear of said abutment, and means to hold said blades together.

2. In a cutting tool of the character described, a pair of blades, a pair of handles,

one blade being rigidly connected to one of said handles, a forwardly faced shouldered abutment on the same handle, an offset bend at the rear of the other blade bearing upon and supported against strain by said abutment, said offset bend being pivotally connected to the other handle, the latter being pivotally connected to the first mentioned handle to the rear of said abutment, said abutment being in a plane at one side of the plane of the blade rigidly connected to one of the handles, and means to hold said handles together.

3. In a cutting tool of the character described, a pair of blades, a pair of pivotally connected handles, one of the blades being rigidly connected to one of the handles, a forwardly faced abutment shoulder on that handle to which the blade is rigidly attached, an offset bend on the other blade, the outer end of said bend being pivotally connected to the other handle, the back of said bend intermediate its length being arranged to both slide and tilt on said offset as said handles are moved to and fro.

4. In a cutting tool of the character described, a pair of blades, a pair of pivotally connected handles, one blade being rigidly carried by one handle, the other blade being pivotally connected to the other handle, an angular bend in the last mentioned blade forming a cam at its rear, a forwardly faced abutment on that handle which carries the rigid blade, said cam being arranged to slide and tilt on said abutment as the handles are moved to and fro, and means to hold said blades together comprising a slot in the bent part of the blade which is pivotally connected to one of the handles, and a headed stud standing in said slot and connected to the rigid handle forward of the abutment.

5. In a cutting tool of the character described, a pair of blades, a pair of pivotally connected handles, one of the blades being rigidly connected to one of the handles, a forwardly faced abutment shoulder on that handle to which the blade is rigidly attached, an offset bend on the other blade, the outer end of said bend being pivotally connected to the other handle, the back of said bend intermediate its length being arranged to both slide and tilt on said offset as said handles are moved to and fro, the cutting edge of the pivotally carried blade being transversely notched.

EDGAR BUELL.
